UNITED STATES PATENT OFFICE.

FRANK C. VAN ETEN, OF CHICAGO, ILLINOIS.

PORTABLE DRAFTING OUTFIT.

1,390,181.

Specification of Letters Patent. Patented Sept. 6, 1921.

Application filed November 11, 1920. Serial No. 423,241.

To all whom it may concern:

Be it known that I, FRANK C. VAN ETEN, a citizen of the United States, residing at Chicago, in the county of Cook and State 5 of Illinois, have invented certain new and useful Improvements in Portable Drafting Outfits, of which the following is a specification.

This invention has to do with improvements in portable drafting outfits; and has reference to an outfit which is especially intended for the use of draftsmen and engineers in the field. The drafting outfit of the present invention is so arranged that the T-square 10 may be folded up and when folded will be of the proper size and shape to conveniently wrap into the foldable paper carrier and table.

One of the objects of the invention is to so 20 arrange the paper carrier that the paper will be very effectively protected against the elements, when the carrier is rolled up. Another object of the invention is to provide an improved form of foldable T-square; and to 25 so arrange and proportion the same with respect to the paper carrier that the folded T-square may be very conveniently transported with the paper carrier itself.

Other objects and uses of the invention 30 will appear from a detailed description of the same which consists in the features of construction and combinations of parts hereinafter described and claimed.

In the drawings:

Fig. 1 shows a plan view of the paper carrier unfolded and with the T-square folded up and lying across the paper carrier;

Fig. 2 shows a view similar to that of Fig. 1 with the exception that a sheet of paper has 40 been torn off from the binding edge and set into place on the celluloid strip, and the T-square has been unfolded and set into working position;

Fig. 3 shows a section taken on the line 45 3—3 of Fig. 2 looking in the direction of the arrows;

Fig. 4 shows a side view of the folded T-square; and

Fig. 5 shows a cross section of the paper 50 carrier and T-square when the parts are rolled up and out of use.

The paper carrier comprises a strip of leather or other suitable water proof material 6, the left hand edge 7 of which serves 55 as the binding edge. To this left hand edge is secured a steel strip or bar 8 by

means of a series of large head screws 9 which are preferably threaded up from beneath. A number of sheets of drafting paper 10 may have their left hand edges clamped 60 between the strip 6 and the bar 8 as will be clearly evident particularly from Fig. 3.

Ordinarily a strip of celluloid or other similar material 11 will be placed over the pile of drafting sheets 10 and will also have 65 its left hand edge clamped by the bar 8. When it is desired to use the drafting outfit, the strip of celluloid may be turned back, one of the sheets of paper may be torn off adjacent to the binding edge, the celluloid strip 70 may then be laid down smoothly and the strip of paper may then be set on top of the celluloid and secured in place by the use of thumb tacks 12 as clearly shown in Fig. 2.

From the foregoing it will be evident that 75 the celluloid strip and the water proof strip 6 together serve as a weather proof protection for the intervening pile of drafting sheets; while at the same time the celluloid strip and the drafting sheets below it also 80 serve as a convenient medium into which the thumb tacks may be forced in order to hold a drafting sheet in place while the outfit is being used in the field.

I have provided a T-square 13 for use in 85 conjunction with this outfit. The said T-square is of such proportion and construction that it may be folded up into a compact element of substantially the same length and width as the binding bar 8, so that it may 90 be laid against said binding bar and rolled up with the same when the outfit is rolled up as shown in Fig. 5. This T-square includes the central and outer members 14 and 15 respectively, which are hinged together 95 at the point 16. An inner end member 17 is secured to the inner end of the section 14 but is offset as shown in Figs. 3 and 4. If desired, the sections 14 and 17 may be formed integral with each other as shown in Fig. 4. 100 The parts are so proportioned that when the upper end member 15 is folded up against the member 14 it comes flush with the shoulder 18 adjacent to the end member 17.

Beneath the end member 17 is pivoted the 105 head 19. This head is of substantially the same width as the members 14, 15 and 17, and is pivoted in such a manner that when the head lies parallel to the body portion of the T-square it substantially occupies the 110 space beneath the end member 17 and adjacent to the shoulder 21, the T-square having

substantially the same length when folded as the length of the binding bar 8.

The pivotal point 20 for the head 19 is so arranged that it can be loosened in order 5 to turn the head 19 around to the desired angle for service as shown in Figs. 2 and 3. At such time there is left a sufficient clearance outside of the shoulder 21 to enable the T-square to be used with convenience.

10 While I have herein shown and described only a single embodiment of my present invention, still I do not limit myself to the said embodiment except as I may do so in the claims.

15 I claim:

1. A portable drafting outfit comprising in combination a paper carrier including a sheet of flexible water proof backing material, a clamping bar removably secured to 20 one edge thereof and extending the full dimension of said edge, a sheet of celluloid having one edge between said bar and the adjacent edge of the water proof backing sheet, a plurality of drafting sheets having 25 their edges between the edge of the sheet of celluloid and said edge of the water proof backing sheet, means for clamping the bar and the water proof backing sheet together to thereby retain the edges of the sheet of celluloid and of the drafting sheets in position, 30 and a foldable T-square in conjunction with said paper carrier and comprising a central bar, an end bar hinged to one end thereof, an offset member on the inner end of the central bar, and having a shoulder adjacent to the 35 position of the end of the hinged bar when folded, and having another shoulder on its under side, and a head pivoted to the under side of the offset member in position to clear the under shoulder, and of suitable dimensions to enable said head to seat against the outer edge of the clamping bar of the paper carrier, said foldable T-square when folded having substantially the same length and 40 width as said clamping bar, substantially as described.

2. A portable drafting outfit comprising in combination a paper carrier including a sheet of flexible water proof backing material, a clamping bar removably secured to one edge thereof, a sheet of celluloid having one edge between said bar and the adjacent edge of the water proof backing sheet, a plurality of drafting sheets having their edges 55 between the edge of the sheet of celluloid and said edge of the water proof backing sheet, means for clamping the bar and the water proof backing sheet together to thereby retain the edges of the sheet of celluloid and of the drafting sheets in position, and a foldable T-square in conjunction with said paper carrier and comprising a central bar, an end bar hinged to one end thereof, an offset member on the inner end of the central bar, and having a shoulder adjacent to the 60 position of the end of the hinged bar when folded, and having another shoulder on its under side, and a head pivoted to the under side of the offset member in position to clear the under shoulder, and of suitable dimensions to enable said head to seat against the outer edge of the clamping bar of the paper carrier, said foldable T-square when folded having substantially the same length and 65 width as said clamping bar, substantially as described.

3. A foldable drafting T-square comprising in combination a central bar, an end bar hinged to one end thereof, an offset member on the other end of the central bar, and having a shoulder adjacent to the position of the end of the hinged bar when 70 folded, and having another shoulder on its under side, a head pivoted to the under side of the offset member in position to clear the under shoulder, and means for locking the head of the T-square to said offset member whereby the head of the T-square may be turned into a position parallel to the central bar and the end bar may be folded over against the central bar, substantially as described.

FRANK C. VAN ETEN.
